WINDOW SASH FASTENER

George Z. Guinard, South Hadley Falls, Mass.

Application October 25, 1947, Serial No. 782,199

1 Claims. (Cl. 292—238)

1

This invention relates to a window sash fastener of the type for locking a window in a partially opened position, against further opening.

One object of the invention is to provide a fastener of the above type which is simple in construction and economical to manufacture. A further object is to provide construction which facilitates application of the fastener to the sash without the necessity of making precise preliminary measurements.

Other and further objects and advantages will be made apparent in the following specification and claim.

In the drawing which shows an illustrative embodiment of the invention,

Fig. 1 is a sectional view showing the device applied to a sash, the window being closed;

Fig. 2 is a similar view showing the window slightly raised to bring the latch into normal locking position;

Fig. 3 is a similar view showing the parts in the extreme locking position;

Fig. 4 is a sectional view substantially on line 4—4 of Fig. 3 showing a plan view of the fastener;

Fig. 5 is a side elevational view of the fastener removed from the sash;

Fig. 6 is an end elevational view looking from the right in Fig. 5; and

Fig. 7 is a detail fragmentary sectional view showing a slightly modified rail element.

Referring to the drawings the catch housing is shown as comprising a downwardly rearwardly inclined top member 1, inwardly inclined side members 2 and outwardly extending flanges 3 by which the housing is secured to the top horizontal frame member of the lower sash of a window. Members 1, 2 and 3 preferably, and as shown, are formed integral from a single sheet of suitable metal. Pivoted within the housing is a catch member 4 formed with side extensions 5 which engage in bearing openings 6 formed on the side walls adjacent the rear end of the housing. A finger piece 7 extends from the catch member 4 outwardly of the housing. The bearing openings are positioned adjacent the bottom of the housing and the forward extension of the catch member is such that when the finger piece is pressed downwardly to swing the catch to the top of the housing, as shown in dotted lines in Fig. 5, the forward edge of the catch member lies flush with or extends only slightly beyond the top edge of the housing. The catch member has its maximum extent from the housing when in its lowermost position as shown in Figs. 3, 4 and 5.

The flanges 3 are provided with openings 8 for

the reception of screws 9 by which the housing and the parts carried thereby may be secured to the upper horizontal frame member 10 of the lower window sash.

Secured to the side member 11 of the upper window sash is an elongated channel member 12 of desired length. The side flanges 13 of the channel member are formed with vertically spaced opposed notches as indicated at 14. The web of the channel member is formed with openings 15 for the reception of screws 16 by which the channel member is secured to a side member 11 of the upper sash.

In applying the device to the sash the channel member is first screwed in place as shown in Figs. 1—4. With the window closed the upper and lower horizontal frame members 10 and 17, respectively, of the lower and upper sashes are drawn tightly together, as shown in Fig. 1 either by pressing the sashes together or by means of the conventional cam lock, not shown, with which the windows are usually provided. With the sash in this position the housing is placed on the frame member 10, and with the finger piece 7 depressed, is moved toward the channel member 12 until the forward edge of the raised catch member 4 engages the flanges 13 as shown in Fig. 1. The housing is then secured in place by screws 9.

The upper and lower window sashes are customarily guided in their vertical movement between outer and inner guides 18 and 19. Usually there is a slight play between the sash frames and the guides as indicated by the spacing at 20 in Fig. 1. This spacing is shown exaggerated in the drawings for the sake of clearness. Within reasonable limits my improved construction provides proper operation in spite of looseness of the sash in the guides. For example, assuming the degree of play shown in Fig. 1, when the lower sash is slightly raised the forward edge of the catch 4 engages in the lowermost notches 14 and, on continued upward movement of the lower sash, spreads the upper and lower sashes, wedging them tightly against the guides as shown in Fig. 2, preventing further opening movement. Where the sashes are exceptionally loose the catch may move to its extreme lower position as shown in Fig. 3.

Additional security may be obtained by forming the notches in the channel member as slightly more than a semi-circle as shown at 21 in Fig. 7.

As will be obvious when finger piece 7 is held depressed to maintain the forward edge of the catch member 4 in its uppermost position the

lower sash can be raised, or the upper sash lowered, to any desired extent and the catch released to engage in any selected pair of notches 14. The window is thereby locked against increased opening but may be closed without resistance, the catch sliding ratchet fashion in the closing direction of movement. It will also be seen that the top of the housing prevents the catch from being thrown into an inoperative position by a sharp blow on the outside of the sash as is the case in many prior art devices of this type.

What I claim is:

A sash fastener combination which comprises a housing consisting of a single piece of sheet metal the center portion of said sheet providing a downwardly and rearwardly inclined top member wider at its forward edge than at its rear edge, intermediate side portions of the sheet being bent downwardly to form rearwardly converging vertical side walls and the side edge portions being bent outwardly to provide horizontal flanges, said flanges being formed with openings for attaching the housing to the lower sash of a window, the so-formed housing being completely open at its forward and rear ends, a catch plate in the form of a piece of sheet metal wider at its forward end than at its rear end, and substantially conforming to the horizontal cross sectional shape of the interior of the casing, said catch plate being provided at its side edges with outwardly extending opposed trunnion portions which freely and

pivotal engage in openings formed in the side walls of the housing closely adjacent the lower edges of said side walls at the rear of the housing, the forward edge of said catch plate extending slightly outwardly of the forward end of the housing and the rear end portion of the catch plate extending outwardly of the rear end of the housing to form a finger piece, said rear end portion of the catch plate being bent upwardly along 10 a line closely adjacent to, and to the rear of, said trunnions to lie in a plane at an angle to the plane of the forward portion of the catch plate, and a channel member adapted to be secured to the upper window casing, the horizontally spaced 15 free edges of the sides of the channel being formed with a series of vertically spaced notches selectively engageable by the forward edge of the catch plate when the latter is swung to a position below the top of the housing.
